(57) CLAIM

The ornamental design for wedge golf club head, as shown and described.

DESCRIPTION

FIG. 1 is a perspective back view of my new design for a wedge golf club head;

FIG. 2 is a back view thereof;

FIG. 3 is a sole view thereof;

FIG. 4 is a top view thereof;

FIG. 5 is a front view thereof;

FIG. 6 is a heel view thereof; and,

FIG. 7 is a toe view thereof.

The broken line showing on the striking face, the rear of the golf club head and on the hosel are for illustrative purposes only and forms no part of the claimed design.
